DRILL BIT

Edward B. Williams, Jr., Greenville, Tex.

Application November 19, 1943, Serial No. 510,946

8 Claims. (Cl. 255—61)

This invention relates to drill bits, particularly of the type used in drilling earth formations as disclosed in my application for patent, Serial No. 497,898, filed August 9, 1943, now Patent No. 2,371,489, granted Mar. 13, 1945; the present application being directed to improved features which better adapt the bit for drilling chert and similar rock formations.

Other objects of the invention are to provide a drill bit having a cutting face bedded with cutting elements such as diamonds and shaped to provide a suitable starting surface without excessive pressure at the point of the bit; to provide a drill bit having a tapered drilling face transversed with channels or grooves between the cutting elements so as to provide movement of cuttings and drilling fluid across the face of the bit when the bit is in operation; and to provide the bit with watercourses cooperating with the cutting receiving grooves to facilitate removal of the cuttings.

In accomplishing these and other objects of the invention hereinafter pointed out, I have provided improved structure, the preferred form of which is illustrated in the accompanying drawing, wherein:

Fig. 1 is a perspective view of a drill bit constructed in accordance with the present invention.

Fig. 2 is a vertical central section through the bit.

Fig. 3 is an end view of the drilling face of the bit.

Fig. 4 is an enlarged section through the drilling face of the bit, particularly illustrating the cutting grooves intermediate the rows of cutting elements.

Referring more in detail to the drawing:

1 designates a drill bit constructed in accordance with the present invention and which is particularly adapted for drilling chert and similar rock formations. The bit includes a substantially cylindrical body 2 formed of material capable of withstanding strains and pressures incidental to drilling, and having shape to provide a substantially frusto-conical end 3 having a substantially flat central portion 4. The outer marginal edges of the face 3 round into the cylindrical side face 5 of the bit body as indicated at 6, Fig. 2. Formed on the upper end of the body 2 is an externally threaded neck 7 for attachment of the bit to a drill pipe not shown. The body of the bit is provided with an axial bore 8 extending inwardly thereof from the neck 7 and

which terminates short of the flattened area 4 to provide a wall thickness 9 therebetween.

The exterior of the side face portion 5 and the conical end face 3 are provided with a plurality of recesses 10 for anchoring a matrix 11. The matrix 11 is formed of relative hard and tough material such as bronze or a similar metal alloy or a plastic capable of being cast upon the body of the bit and having the property for retaining cutting elements such as diamonds 12 securely embedded therein. The matrix material is also selected so that it is capable of wearing to expose cutting points of the diamonds when the drill bit is being used for drilling in chert or similar formations. The matrix is of a thickness to provide ample strength and depth to bed the cutting elements, and to accommodate a plurality of grooves or passageways 13 for movement of cuttings to primary and secondary water courses 14 and 15. The matrix extends upwardly and is shaped to provide a cylindrical face 16 and also serves to bed cutting elements 17 to provide a reaming face 18 for the drill bit.

23 The drilling face of the bit substantially conforms in shape to the end face of the body 2 in that it includes a central flat area 19 of sufficient size to provide a starting surface for the bit when cutting chert formations. The outer portion of the end face tapers in cone-like formation at a suitable angle, for example, substantially 15°, and joins with the reaming face 18 on a rounding curve 20.

In order to offset the excessive pressure acting at the center of the bit upon initial starting of a cutting operation, the central portion of the flat area 6 has an inwardly extending cone-like recess 21 so that when the drill bit is first placed in operation on the hole bottom only the flat area surrounding the recess begins to cut the formation. With this arrangement, the initial cutting area is limited so as to facilitate starting of the bit in chert and similar formations.

45 The cutting elements 12 bedded in the drilling face of the bit are shown arranged in spiral rows 22 at the side of the grooves 18 which provide for passage of the cuttings produced by the cutting elements. The cutting elements are preferably oriented within the matrix with their axes at substantially 15° relatively to the plane of the cutting face of the bit and with the points thereof extending in the rotational direction of the bit. The cutting elements 17 are similarly bedded within the matrix to cover the reaming surface thereof;

however, the cuttings receiving grooves may be omitted in this section of the bit.

The primary watercourses 14 are formed in the matrix material and extend substantially radially from the axis of the drill bit to the periphery thereof and join with upwardly extending watercourses 23 formed in the reaming face 16 and which terminate above the reaming face as indicated at 24 within a bevelled periphery 25 of the matrix.

The inner ends of the primary watercourses are connected with the bore 8 by ports 26, at least one of which connects with and discharges into the recess 21. Certain of the watercourses also connect with the recess 21 as indicated at 27 to effect discharge of material which is cut and broken off by the cutting elements 28 embedded within the surface of the recess as best shown in Fig. 2.

The secondary watercourses 15 extend spirally from the primary watercourses, thus the drilling face is divided into a series of segments 29 having the rows of spirally arranged cutting elements and intermediate passageways 13 with the sections traversed by the secondary courses. The innermost secondary passageways preferably connect the adjacent primary watercourses as indicated at 30, and the outermost secondary watercourses connect the primary watercourses at the periphery of the bit with upwardly extending secondary watercourses 31 as best shown in Fig. 1. The groove-like passage ways intermediate the rows of cutting elements are thus connected by the secondary and primary watercourses so that when the cuttings enter the grooves they move therealong to pass through the watercourses and are carried to the top of the wall by the drilling fluid.

In making the bit, a mold is formed of sand and suitable binder and is shaped to provide the drilling and reaming faces, the watercourses, and the cuttings receiving grooves. The cutting elements are then temporarily secured to the surface of the mold in the desired patterns, after which the bit body is inserted into the mold and the matrix material is poured therearound. The matrix material flows in and around the cutting elements and into the recesses 18 for forming keys 32 to anchor the matrix from movement on the body member.

When the matrix material has set, the bit is removed from the mold and the cutting elements are rigidly embedded in the matrix material and the matrix material is securely anchored to the body. Since the mold is shaped to form the sector-shaped cutting faces, watercourses, and grooves, these portions of the bit are complete; but it is necessary to drill the water ports or channels 26 to connect with the bore 8.

When the bit is to be used, it is attached to the lower end of a drill pipe as in conventional practice and the assembly lowered to the bottom of the borehole. The drill pipe is then rotated by a conventional rotary drilling rig not shown. During rotation of the bit, the flat central drilling face starts the cut and as the operation progresses the cut extends to the periphery of the drilling face of the bit. Thus, by starting the cutting operation over a limited area, the cutting operation is facilitated and since the recess is provided at the center of the bit, the destructive effects of excessive pressure at this point is avoided. However, as the cutting area is extended the cutting elements within the face of the recess 18 become effective to cut the point-

like formation which extends thereinto. Should this formation break off the watercourses connected therein are of sufficient size to readily discharge the material under the propelling influence of the drilling fluid discharged through the port that is connected with the recess.

During the initial rotation, the matrix material wears sufficiently to expose the cutting elements to render them effective for cutting the formation, the cuttings of the formation being discharged into the passageways 13 and the cuttings are discharged therethrough into the watercourses for discharge into the borehole above the body of the bit. During rotation of the bit 15 the cutting elements in the reaming surface of the bit will prevent any tendency for the bit to bind in the borehole.

From the foregoing it is obvious that I have provided a bit structure particularly adapted for drilling chert and similar formations.

What I claim and desire to secure by Letters Patent is:

1. A rotary drill bit including a body having a drilling face provided with spirally arranged cuttings receiving grooves, and cutting elements bedded in said face on respective sides of said grooves, said face having watercourses dividing said face into sections and connecting said grooves, and said sections having secondary watercourses extending transversely of said grooves.

2. A rotary drill bit including a body provided with a substantially frusto conical drilling face and having a recess in the axis of said bit, said body having a substantially axial bore and having a port connecting the bore with said recess at a point offset from the rotational axis of the bit for passage of a drilling fluid, therethrough, the drilling face having a watercourse extending from the recess across said drilling face.

3. A rotary drill bit including a body provided with a substantially frusto conical drilling face and having a recess in the axis of said bit, said body having a substantially axial bore connected with said recess for passage of a drilling fluid to the drilling face, said drilling face having a watercourse extending from said recess to the periphery of the bit, and cutting elements bedded in said face including walls of said recess, said cutting elements in the drilling face being arranged in substantially spiral rows, the drilling face having grooves intermediate said rows of cutting elements and having connection with said watercourse.

4. A rotary drill bit including a body, a matrix on said body having a drilling face and having a recess in the axis of said bit, said body having a substantially axial bore connected with said recess for passage of a drilling fluid, said drilling face having a watercourse extending from said recess to the periphery of the bit, and having cuttings receiving grooves connected with the watercourses, and cutting elements bedded in said matrix between said grooves.

5. A rotary drill bit including a body provided with a substantially frusto conical drilling face and having a recess in the axis of said bit, said body having a substantially axial bore connected with said recess for passage of a drilling fluid, said drilling face having a watercourse extending from said recess to the periphery of the bit, and having substantially spiral cuttings receiving grooves connected with the watercourse, and cutting elements bedded in said face including walls of said recess, said cutting elements being

arranged in substantially spiral rows between said grooves.

6. A rotary drill bit including a body provided with a substantially frusto conical drilling face and having a recess in the axis of said bit, said body having a substantially axial bore connected with said recess for passage of a drilling fluid, said drilling face having a watercourse extending from said recess to the periphery of the bit and cutting elements bedded in said face, said cutting elements being arranged in substantially spiral rows, the drilling face having cuttings receiving grooves intermediate said rows of cutting elements and having connection with said watercourse.

7. A rotary drill bit including a body, a matrix material keyed to said body for forming a drill-

ing face provided with spaced spirally arranged cuttings receiving grooves, and cutting elements bedded in said matrix material between said grooves, said face having watercourses dividing said face into sections and connecting said grooves.

8. A rotary drill bit including a body having a drilling face provided with spirally arranged cuttings receiving grooves, cutting elements embedded in said face on the respective sides of said grooves, said drilling face having watercourses extending transversely of the grooves and having secondary watercourses connected with the first-named water courses, and extending angularly across the cuttings receiving grooves.

EDWARD B. WILLIAMS, JR.
